FLUE CUTTER

Application filed April 18, 1932. Serial No. 606,014.

The present invention relates to flue cutters and the primary object of the invention is to provide an improved front and flue cutter of extremely simple construction, 5 strong in its mechanical make up, and a cutting tool of this character which may be manufactured at a relatively low cost.

A further object of the invention is to provide a flue cutter embodying an adjustable gauge or flue sheet stop adjustable toward and from the cutting disc, together with positive feed means for automatic projection and retraction of the cutting disc, said feed means being movable by the same 15 threads which permit adjustment of the gauge or flue sheet stop.

A further object of the invention is to provide a flue cutter which may be either power driven or hand operated and embodying a 20 construction permitting ready and easy assembling and renewing of parts.

Other objects and advantages of the invention will be apparent during the course of the following detailed description, taken in 25 connection with the accompanying drawings forming a part of this specification and in which drawings:

Figure 1 is a side elevation of the improved flue cutter and showing the cutting disc in a retracted position.

Figure 2 is a longitudinal section thru the cutter and showing the same in position for use.

Figure 3 is a transverse section on the line 33 3—3 of Figure 2.

Figure 4 is an enlarged fragmentary section on the line 4—4 of Figure 1.

Figure 5, 6 and 7 are transverse sections on the respective lines in Figure 2.

Figure 8 is an enlarged fragmentary elevation showing the guide opening for the cutting disc.

In the drawings and wherein similar reference characters designate corresponding 45 parts throughout the several views, the letter A designates a tube sheet thru which the boiler tube B projects to be cut off for beading over by the improved flue cutter C.

The flue cutter C comprises a tubular housing or casing 5 being of such external diam-

eter to be slidably inserted in the end of the tube B and including separable front and rear tubular sections 6 and 7 respectively. The rear or main tubular casing section 7 which has a length considerably greater 55 than that of the front casing section 6 is provided throughout the major portion of its length with the external screw threads 8 providing a threaded casing portion for receiving the gauge or flue sheet stop D and 60 the cutter feed means E.

Arranged within the casing 5 to extend thruout the length thereof and serving to axially align the casing sections 6 and 7 is a cylindrical core member 10 which is longitudinally grooved or channeled as at 11 with the channel terminating inwardly of the ends of the core member. This radially opening channel 11 is of substantially rectangular shape in cross section as clearly 70 shown in Figure 7 and at its rear end opens into a transverse passageway 12 formed diametrically thru the core member. Secured to the forward end of the core member 10 as by a cap screw 13 is an end plate 14 having its peripheral portion overlying the forward end of the front casing section 6. The rear end portion of the core member beyond the passageway 12 is formed with an opening 15 for receiving a square shank 16 adapted to receive the socket of the driving means for rotating the cutter. A set screw 17 threaded thru the casing section 7 into engagement with the rear portion of the core member serves to prevent rotation of the 75 core member within the section 7. This set screw 17 and the end plate 14 also serve to retain the sections 6 and 7 in abutting relation at the meeting line 18.

Referring now to the gauge or flue sheet 90 stop D for gauging the distance at which the tube B will be severed beyond the outer face of the tube sheet A, the same comprises a gauge sleeve 20 being internally threaded for threading along the fine threads 95 8 of the casing section 7. The forward portion of the sleeve 20 is formed with an external circumferentially extending groove 21, while the rear portion of the sleeve is formed with an internal annular groove 22. 100

Adapted for mounting upon the forward portion of the gauge sleeve 20 is a gauge member including a ring 23 rotatable upon the forward portion of the gauge sleeve and held for rotation thereon by screws 24 having plain inner end portions for fitting in the external annular groove 21. Projecting forwardly from the ring portion 23 are stop arms 25 which are intended to engage the outer face of the sheet A for limiting insertion of the tool into the tube B. These stop arms 25 as will be observed in Figure 2 engage the sheet A outwardly of the boiler tube, the boiler tube extending between the arms and the tubular casing 5. Arranged within the internal annular groove 22 and conforming to the curvature thereof is a clamping shoe 26 which is threaded along its inner concaved side to fit the threads 8. A clamping screw 27 threaded radially thru the gauge sleeve 20 serves to clamp the shoe 26 against the casing section 7 for retaining the member D in adjusted threaded position with respect to the cutting disc of the tool. The threaded inner side of the shoe 26 is to prevent marring of the threads 8 and a suitable retaining screw 28 threaded thru the rear portion of the gauge sleeve into a slot in the clamping shoe serves to retain the shoe in position beneath the clamping screw 27. The gauge ring 23 is preferably formed with a step as shown in Figure 2 where it receives the ring 23 so as to cut down the over-all diameter of the flue sheet stop and permit use of the tool where the boiler tubes are placed relatively close. The stop arms 25 will not be rotated during the cutting operation owing to the rotatable mounting of the ring portion 23 upon the gauge sleeve 20.

Mounted for longitudinal sliding movement in the channel 7 is a traveller or feed bar 30 provided adjacent its forward end with a wedge portion 31 providing a cam surface 32 for engagement with the inclined inner end of a radially movable cutter block 33. The cutter block 33 is connected by a locking dovetail joint to the wedge portion 31 whereby the cutter block will have positive sliding movement radially of the tool upon longitudinal movement of the traveller 30 in either direction longitudinally of the tool. This dovetail connection between the wedge and cutter block 31 and 33 respectively insures retraction of the cutter block. The traveller bar 30 as will be observed in Figures 6 and 7 is of rectangular shape at its central portion and has a snug sliding fit in the channel 11 so as to be rotated upon rotation of the core member 10.

Referring now to the feed means E for automatic projection and retraction of the cutting means upon rotation of the tool during the cutting operation, the same is adapted to cooperate with the threads 8 providing adjustment for the gauge or flue sheet stop D. This cutter feed means E comprises a feed or travelling nut 35 for threading along the threads 8 and a flanged sliding sleeve 36 having a plain opening for sliding movement along the threads 8. Carried by the travelling nut 35 is a coupling collar 37 having an inturned annular flange 38 at its rear edge for engaging over the outturned flange 39 of the sliding sleeve 36 whereby the sliding sleeve is connected for movement with the travelling nut. The coupling collar 37 is connected at one point to the travelling nut 35 by a suitable screw 40 and at a point diametrically opposite to the screw 40 by a handle 41 threaded thru the collar into the nut and projecting radially of the tool. This manner of connecting the sliding sleeve 36 to the travelling nut 35 permits relative rotary movement of the members 35 and 36. The threaded portion 8 is provided with diametrically disposed, longitudinally formed slots 42 for receiving a coupling pin 44 having its ends suitably anchored in the sliding ring 36. This coupling pin 44 extends thru the transverse passageway 12 and projects thru an opening 45 provided in the rear end portion of the traveller or feed bar 30 whereby the coupling pin imparts longitudinal movement to the traveller as the feed nut 35 is threaded along the threaded casing portion 8. This coupling pin 44 as will be observed is flattened longitudinally of the tool and this formation of the coupling pin permits of the slot 42 being formed relatively narrow so as to not materially reduce the strength of the tubular casing section 7. Thus the coupling pin 44 aside from connecting the traveller bar 30 to the feed means for longitudinal movement thereby also serves to prevent relative rotation of the core member 10 within the sectional tubular casing 5.

The meeting ends of the casing sections 6 and 7 are notched out as at 50 and the core member 10 is provided with extensions 51 which extend into the notches 50. These extensions 51 as will be observed in Figures 1 and 8 extend across the meeting edges 18 of the casing sections and act as locks to prevent relative rotation of the casing sections 6 and 7. Opening thru the core member 10 from the longitudinal channel 11 is a radial guideway 54 of rectangular shape and which opens between the locking extensions 51. This guideway 54 serves to slidably guide the cutter block 33 radially of the axis of the tool. Mounted between the arms 55 formed by bifurcating the outer end of the cutter block 33 is a cutting disc 56 mounted to rotate on an axis extending parallel to the longitudinal axis of the tool. The cutting disc 56 has a diameter greater than the width of the cutter block 33 and the guideway 54 is slotted as at 58 to accommodate

- the cutting edges of the cutting disc and allow for the arms 55 to have bearing contact with the extensions 51 at the outward limit of movement of the cutting block.
- 5 When the tool is assembled, the cutting disc 56 aligns with the meeting line 18 of the casing sections 6 and 7 so that the line 18 acts as a gauge line for co-acting with the forward ends of the stop arms 25 to gauge 70 the distance from the face of the tube sheet at which the boiler tubes will be severed.
- A pair of thrust rollers 60 are provided at the meeting ends of the casing sections 6 and 7 for opposing the thrust of the cutting disc 56 and these rollers are mounted in recesses 61 formed in the core member 10. 75 The rollers are provided at each end with a bearing pin 62 and these bearing pins engage in slots 63 formed in the circumference 80 of the core member 10 at each end of each recess 61. The casing sections 6 and 7 are notched out at their meeting edges as at 64 to provide openings thru which the rollers project slightly beyond the circumference 85 of the tubular casing 5 so as to have rolling contact with the interior of the boiler tube. As will be observed in Figure 4, the roller bearing pins 62 are held in the slots 63 by the tubular casing sections.
- 20 In use, the travelling nut 35 is threaded forwardly along the threaded portion 8 for retracting the cutter block 33 to a point where the cutting disc 56 is moved below the circumferential surface of the casing 5. 90
- 25 The gauge or flue sheet stop B is then rotated along the threaded portion 8 and the forward ends of the stop arms 25 set with respect to the circumferential line 18 which aligns with the cutting disc 56 for determining 95 the amount of projection of the boiler tube beyond the flue sheet. The clamping screw 27 is then tightened for clamping the shoe 26 against the casing to prevent further rotation of the gauge sleeve 20 along 100 the casing. The forward end of the tool is then inserted into the boiler tube until the arms 25 engage the tube sheet A and the tool is now in the proper position for the cutting operation. The handle 41 may either 105 then be grasped by one's hand or preferably rested against a bar inserted into a boiler tube closely adjacent the one being cut so that the handle serves to hold the travelling nut against rotation. Power is 110
- 115 then applied to the coupling shank 16 and the tool rotated, the casing 5 and core member 10, together with the traveller 30 rotating as a unit. The threads 8 are preferably right hand threads and as the tool is rotated the travelling nut 35 and collar 37 remain stationary. This holding of the travelling nut 35 causes the nut, when the tool is rotated in a right hand direction, to be moved rearwardly along the threaded portion 8 toward the shank 16. This rearward 120

movement of the travelling nut 35 imparts a rearward movement to the traveller or feed bar 30 by reason of the coupling pin 44. This rearward movement of the traveller causes the cutter block 33 to be forced radially outwardly by reason of the inclined surface 32 and forces the cutting disc 56 into the boiler tube B as the tool is revolved. After the tube has been severed, the tool is rotated in an opposite or left hand direction so that the travelling nut 35 moves forwardly along the casing and imparts forward longitudinal movement to the traveller 30 for retracting the cutting disc. The tool may then be withdrawn from the boiler 125 tube.

By forming the tubular casing 5 in two sections 6 and 7 divided at the point 18, provides an arrangement whereby the tool may be easily and quickly assembled.

Thus it will be seen that a flue cutter of novel construction has been provided wherein a very fine and positive adjustment of the gauge or flue sheet stop may be had by the external threads 8 extended for a substantial portion of the casing, and which threads also cooperate with the cutter feed means for automatically projecting and retracting the cutter disc in a direction radially of the tool axis.

Changes in detail may be made to the form of invention herein shown and described without departing from the spirit of the invention or the scope of the following claims.

We claim:

1. In a flue cutter, the combination of a tubular casing having an externally screw threaded portion, a core member non-rotatably mounted in the casing, a feed bar longitudinally movable in the core member, a radially movable cutter movable upon longitudinal movement of the feed bar, a gauge in threaded engagement with the threaded portion of the casing, a feed nut threaded upon the threaded portion of the casing, coupling means between the feed nut and feed bar and rotatable with the feed bar, and means for holding the feed nut against rotation for imparting longitudinal movement to the feed bar upon rotation of the casing.

2. In a flue cutter, the combination of a tubular casing having external threads, a core member held against rotation within the casing, a feed bar non-rotatable and longitudinally movable in the core member, a cutter guided for movement radially of the casing by the feed bar, a gauge threaded upon the external threads, adjustment retaining means for the gauge, a feed nut threaded upon said external threads, a coupling sleeve rotatably connected to the feed nut, coupling means between the coupling sleeve and feed bar, and means for holding the feed nut

against rotation during rotation of the casing.

3. In a flue cutter, the combination of a tubular casing having external screw threads, a core member fixed in the casing, a feed bar non-rotatable and longitudinally movable in the core member, a cutter radially movable by the feed bar, a gauge threaded on said screw threads, and cutter feed means including a travelling nut threaded on said screw threads, a flanged collar fixed to the travelling nut and providing an annular groove, a coupling sleeve having a flange engaging in the groove and permitting relative rotation of the nut and sleeve, a coupling pin carried by the sleeve and extending diametrically thru the casing and core member and having fixed attachment to the feed bar, and a handle projecting from the travelling nut to hold the same against rotation while the casing is being rotated.

4. In a flue cutter, the combination of a tubular casing having external screw threads and diametrically disposed slots extending longitudinally of the casing, a core member fixed in the casing having a transverse passageway aligning with said slots, a feed bar non-rotatable and longitudinally movable in the core member and having one end projecting into said passageway, a cutter radially movable by the feed bar upon longitudinal movement thereof, a gauge threaded on said screw threads, a travelling nut threaded on said screw threads, a collar fixed to the travelling nut and having an inturned annular flange providing an annular groove, a coupling sleeve slidable along the casing and having an outturned annular flange engaging in said groove, a coupling pin secured at its ends in the sleeve and being connected midway its ends to the feed bar, said coupling pin being guided in said slots and extending thru said transverse passageway in the core, and a handle connected to the travelling nut to hold the same for feeding along the external screw threads upon rotation of the casing.

5. In a flue cutter, the combination of a tubular casing having external screw threads, a core member fixed in the casing, a feed bar non-rotatable and longitudinally movable in the core member, a cutter radially movable by the feed bar, cutter feed means threaded on said screw threads and having connection with the feed bar for moving the bar longitudinally upon rotation of the casing, and a flue sheet stop comprising a gauge sleeve threaded on said screw threads and having an internal and an external annular groove, an arcuate clamping shoe arranged in the internal groove and having threads at its inner side, means for preventing circumferential movement of the shoe in the groove, a clamping screw for the shoe, a gauge member including a ring por-

tion rotatable upon the gauge sleeve, retaining pins carried by the ring portion and engageable in the external groove of the gauge sleeve, and stop arms projecting from the ring portion.

6. In a flue cutter, the combination of a tubular casing having external screw threads and diametrically disposed slots, a core member fixed in the casing having a longitudinally formed channel and a transverse passageway at the rear end of the channel, a feed bar longitudinally movable in the channel and having a wedge portion at its forward end, a cutter radially movable thru the core member and casing and including a cutter block engageable by the wedge portion, a gauge adjustably threaded on the screw threads, a travelling nut threaded on the screw threads, a coupling sleeve encircling the casing and rotatably carried by the travelling nut, a coupling pin connected to the rear end of the feed bar in said transverse passageway and extending thru said slots with its ends connected to said coupling sleeve, and a handle carried by the travelling nut for holding the nut against rotation.

7. In a flue cutter, the combination of a tubular casing including front and rear tubular casing sections, said rear tubular casing section having external screw threads, a cylindrical core member fitting in the tubular casing and retaining the sections in axial alignment, means connecting the sections against separation, a radially movable cutter movable thru the casing at the abutting ends of the casing sections, a feed bar longitudinally movable in the core member for radially moving the cutter, a flue sheet stop threaded on said screw threads, cutter feed means threaded on the screw threads and having coupling means connected with said feed bar, and a handle for holding the cutter feed means against rotation.

8. In a flue cutter, the combination of a tubular casing including front and rear casing sections, said rear casing section being of greater length than the front casing section and having external screw threads, a cylindrical core member fitting in the casing and retaining the sections in axial alignment, means preventing rotation of the core member in the casing sections, locking extensions on the core member projecting into notches at the abutting ends of the casing sections, a guide way formed in the core member between the extensions, a cutter including a cutter block guided in the guide way and a cutting disc aligning with the meeting edges of the casing sections, a feed bar longitudinally guided in the core member for imparting radial movement to the cutter, a gauge member threaded on the screw threads of the rear casing section and having forwardly extending stop arms, and cutter feed means including a traveller

threaded on the screw threads of the rear casing section and coupling means rotatably carried by the traveller and secured to the feed bar, and a handle for holding the traveller against rotation.

9. In a flue cutter, the combination of a tubular casing including front and rear sections, a core member securing the sections in axial alignment, a feed bar longitudinally movable in the core member, a cutter radially movable by the feed bar at the abutting ends of the casing sections, a flue sheet stop adjustable on the rear casing section, cutter feed means for moving the feed bar longitudinally upon rotation of the casing, and thrust rollers journaled in the core member to extend across the abutting ends of the casing sections, said rollers being held against displacement by the casing sections when assembled in abutting relation.
